GAS-ENGINE.

1,130,419.

Specification of Letters Patent.

Patented Mar. 2, 1915.

Application filed January 19, 1909. Serial No. 473,046.

To all whom it may concern:

Be it known that I, ROBERT MILLER, a citizen of the United States of America, residing at New York city, in the county of New York and State of New York, have invented certain new and useful Improvements in Gas-Engines, of which the following is a specification, reference being had therein to the accompanying drawing.

10 This invention relates to vacuum exhaust gas engines wherein a piston is used for the double purpose of imparting the result of the explosion to the crank-shaft, and of creating a vacuum in a separate chamber to draw out the products of combustion which linger after the force of the exhaust becomes spent.

20 My object is to provide an engine of the above type in which the explosion chamber will during all loads be much more equally scavenged, kept cooler, and receive a more constant mixture, thereby obtaining greater flexibility of action, power, durability and efficiency, and also effecting a greater saving 25 in fuel and lubricants.

It should be explained beforehand that the work of scavenging the cylinder is proportionate to the strength and volume of the vacuum. Therefore it is apparent that a 30 vacuum created in the crank-case by the return stroke of the power piston, as in an ordinary two-cycle engine, is necessarily weak owing to leakage around the crank bearings. In my device the vacuum is 35 formed in a separate tight vacuum chamber wholly disconnected from and independent of the crank-case, whereby leakage is reduced to a minimum, and a high, strong and efficient vacuum can be created of sufficient volume.

40 Furthermore, I provide a method of and apparatus for shutting off the vacuum chamber from the explosion chamber before opening the fuel inlet, thereby not depending on displacement of old 45 charge by the new charge, and preventing the fuel from following the residual spent gases out of the explosion chamber and becoming wasted. Hence my invention comprises virtually the same method of expulsion 50 as the four cycle engine in that it first permits the engine to exhaust by release of the fired gases which pass out under their

own pressure, and secondly by removing a fixed quantity of the residual products of combustion. An additional source of cooling consists in the reflex shrinkage of the burned gases as they pass from the power cylinder to the vacuum cylinder due to the drop in temperature owing to the previous expansion caused by differences in pressure. 55 Therefore the vacuum chamber should be as large as possible in proportion to the size of the power cylinder.

It is also a great advantage and is my object to remove as much burned gas from the power cylinder on light loads as on full loads. If less burned gas be removed on light loads than on heavy loads, then the fresh charge will be fouled with too great a proportion of burned gas, whereby ignition is rendered uncertain and the flexibility of the engine unreliable. In this respect my object is to duplicate as near as practicable, the positive equal displacement of the burned gas which takes place in the four 75 cycle engine at all loads.

To these ends my invention consists in the peculiar features and combinations of parts more fully described hereinafter and pointed out in the claims.

80 In the accompanying drawings, Figure 1 represents a sectional elevation of my invention, and Figs. 2 and 3 are modifications.

85 For purposes of illustration, the power cylinder 1, vacuum cylinder 2, and crank case 3 are shown cast in two pieces bolted together, no water jacket or cooling flanges being shown, although in practice one or the other will probably be desirable. The differential piston comprises two principal 90 elements, the power piston 4 and vacuum piston 5. This vacuum piston and cylinder are much larger in diameter than the power cylinder and its piston, whereby ample room is allowed in the vacuum cylinder for the 95 reception of the burned residual gases which are drawn out of the power cylinder on the down-stroke of the two pistons. Both pistons are preferably cast in one piece and are provided with the usual packing rings 6 and 100 are connected to a pitman 7 which is attached to a crank 8 on crank shaft 18. The valve connections consist of a pneumatically actuated inlet valve 9 controlling the

admission of the explosive mixture which is supplied to pipe 20 from any suitable source or by any well known means. On the opposite side of the power cylinder is located an exhaust port 10 placed near the end of the outstroke of the piston and in communication with an exhaust pipe 11 containing a check valve 12 seated to open outwardly and held to its seat by flat spring 13 and rendered accessible by cover 14 through which the stem of the valve passes. A by-pass 15 establishes communication between the two cylinders and is commanded by a rotary valve 16 having an arm 19 which may be connected with any moving parts of the engine and timed to operate as presently described. The spark plug 21 in the head of the cylinder 1 fires the gas at the proper moment as will now be described.

Assuming that a proper charge of gas has just been admitted to the power cylinder and is under compression, the explosion will drive the piston downward until the exhaust port 10 is uncovered, whereupon the released products of combustion pass out through the exhaust pipe 11 lifting the check valve 12 against the spring 13 in doing so. The continued downward movement of the two pistons will create a strong vacuum in the vacuum cylinder 2, whereupon the by-pass valve 16 will be thrown open after the close of the exhaust and the residual gas drawn into the vacuum cylinder. An equilibrium will then be established between the two cylinders. This leaves a vacuum in the power cylinder practically free from burnt gases and in good condition to draw in a fresh explosive charge. The further rotation of the crank shaft closes the by-pass valve and seals the explosion chamber and the inlet valve having been given the proper "lead" is then uncovered and opened by the vacuum left in the explosion chamber and draws in a fresh charge of explosive gases. When the power piston moves upward toward compression the vacuum piston follows, expelling the dead gases from the vacuum chamber through the by-pass 15 and exhaust 12. The continued upward movement of the power piston compresses the combustible gases, and when they are ignited the cycle of operations just described is repeated.

In clearing the cylinder of the spent gases, they first pass out of the exhaust through the power of their own pressure, but a certain portion always lingers in the power cylinder, and it is this portion which is removed through the medium of the vacuum that follows. The exhaust port is timed to close in advance of the opening of the inlet port so that it is impossible for any of the fresh charge of gas to be drawn out through the exhaust port with the spent gases and wasted. In this respect my invention effects

great economy in the consumption of fuel as the double exhaust construction which removes the residue of burned gases, prevents the fouling of the fresh charge and produces a much more uniform explosion and 70 flexible and reliable operation under both light and heavy loads.

It is apparent that the particular mechanism whereby I accomplish these advantages might be varied in numerous ways such, for 75 instance, as shown in Fig. 2 wherein a vacuum chamber 22 is separated farther from the power cylinder 29 through the medium of a pipe 23 having a valve 28 which is adapted to coöperate with an exhaust pipe 30 24 and valve 25. In this case the power cylinder 29 is provided with an inlet pipe 26 and rotary valve 27, and a separately driven vacuum pump, or attached pump or ejector.

Another modification is shown in Fig. 3, 85 wherein a pair of pistons of equal diameter are connected by rod 30, one piston being the power piston and the other the vacuum piston. Between the two is located a chamber 31 formed by disks 32. The power cylinder 90 is connected with the vacuum cylinder and the piping and valves are all arranged and adapted to operate in substantially the same manner as those shown in Fig. 1.

Having thus described my invention, what 95 I claim as new and desire to secure by Letters Patent, is:

1. In a gas engine of the two-cycle type, an explosion cylinder and a piston working therein, a vacuum chamber, a valved by-pass 100 between the explosion chamber and the vacuum chamber, a valved exhaust port for the explosion chamber, a fuel inlet port therefor, and means for opening the said by-pass and establishing communication between the interior of the explosion cylinder and the vacuum chamber after the force of the exhaust blast has practically spent itself.

2. In a gas engine, a pair of cylinders of different size forming respectively explosion 110 and vacuum chambers, a differential piston in said cylinders, in combination with means consisting of a valved by-pass leading from the explosion chamber to the vacuum chamber, a valved exhaust port, a fuel inlet port, 115 means for opening the by-pass and closing the exhaust port and establishing communication between the two cylinder chambers after the force of the exhaust blast has practically spent itself, and an inlet valve for 120 opening the valve inlet to the explosion chamber while the by-pass is closed.

3. In a gas engine, the combination of a pair of cylinders of different size forming respectively explosion and vacuum chambers, a differential piston, a valved by-pass leading from the explosion chamber to the vacuum chamber, a valved exhaust port, a fuel inlet port, valve mechanism which 125 opens the by-pass and closes the exhaust port 130

and establishes communication between the two cylinder chambers after the force of the exhaust blast has practically spent itself, and means for opening the fuel inlet to the 5 explosion chamber while the by-pass is closed.

In testimony whereof I affix my signature in presence of two witnesses.

ROBERT MILLER.
